CLAIM

The ornamental design for child's pocketed bed rest cushion, as shown and described.

DESCRIPTION

FIG. 1 is a perspective view of the child's pocketed bed rest cushion showing my new design, on an enlarged scale;

FIG. 2 is a front elevational view thereof;

FIG. 3 is a back elevational view thereof;

FIG. 4 is a top plan view thereof;

FIG. 5 is a bottom plan view thereof; and

FIG. 6 is a side elevational view thereof, the opposite side being a mirror image.

FIG. 1

FIG. 2

FIG. 3

FIG. 4

FIG. 6
